ROAD JOINT SUPPORT

Elmer J. Webb, Syracuse, N.Y., assignor to The Eastern Company, a corporation of Connecticut
Filed Dec. 27, 1960, Ser. No. 78,542
1 Claim. (Cl. 94—8)

This invention relates to and has as an object a new and improved road joint support arrangement for supporting adjacent sections or slabs of a concrete roadway.

Concrete roadways are divided into a plurality of adjacent sections or slabs and the joint between each adjacent section or slab must be supported in a manner which prevents the sections from raising or lowering with respect to each other, but yet at the same time, the manner of support for the sections must permit the normal expansion and contraction of the sections to take place, which in turn, operates to open or close the joint. In addition, the joint support must be so constructed as to transfer the moving loads of vehicles on the roadway from one adjacent section or slab to the other in a manner to prevent the raising or lowering of the sections in the joint.

Accordingly, it is a more specific object of this invention to provide a new and improved road joint support arrangement which will prevent adjacent sections of a concrete roadway from raising or lowering with respect to each other, and wherein the support arrangement will permit normal expansion and contraction of the concrete to take place without affecting the road joint support.

The invention consists in the novel features and in the combinations and constructions hereinafter set forth and claimed.

In describing this invention, reference is had to the accompanying drawings in which like characters designate corresponding parts in all the views.

In the drawings:

FIGURE 1 is a perspective view, greatly foreshortened, of the road joint support arrangement shown in position between the side forms just prior to the pouring of the concrete to form the roadway;

FIGURE 2 is a cross section elevational view showing a pair of members comprising one embodiment of the invention for forming the road joint support wherein the members are shown embedded in adjacent concrete sections forming the roadway;

FIGURE 3 is a view similar to FIGURE 2 showing a different embodiment of the invention;

FIGURE 4 is a cross sectional view taken looking in direction of the arrows of line 4—4 on FIGURE 2;

FIGURE 5 is a cross sectional view taken looking in direction of the arrows of line 5—5 on FIGURE 3;

FIGURE 6 is a fragmentary cross sectional view taken looking in direction of the arrows of line 6—6 on FIGURE 2; and

FIGURE 7 is a fragmentary cross sectional view taken looking in direction of the arrows in line 7—7 on FIGURE 3.

In FIGURE 1, the side form members 10 and 12 for a roadway are shown positioned on the subgrade 14 and a joint support arrangement, generally indicated by the number 16, is shown as being disposed transversely across the roadway between the side form members 10 and 12.

The support arrangement briefly described comprises a plurality of pairs of complementary members which are joined together at their intermediate portions in a rigid manner, and wherein each of the members comprises a leg or supporting portion which is adapted to rest on the subgrade surface, a center or intermediate portion comprising a load-transfer portion which extends across

2

the joint and into engagement with a load-transfer-receiving portion formed in the center or intermediate portion of the other member, and a rearwardly extending compression member. The load-transfer portions of each of the members are fixedly and rigidly secured in the load-transfer-receiving portion of the other of said members forming an interlocked joint support pair in a manner which prevents any vertical or lateral displacement of the members with respect to each other, but which will, when the members are subjected to tensile or compressive loads, permit longitudinal or horizontal movement of the members with respect to each other. Each pair of members are spaced apart and are interconnected by a central, transversely, extending plate extending across the entire width of the roadway, and the plate is supported by and between each of the pairs of members.

In one embodiment, shown in FIGURE 2, the pair of complementary members are shown embedded in the adjacent sections or slabs 18 or 20 of the concrete roadway. In that view, each of the members comprises a central or intermediate portion 22 which is formed with an aperture 24 to reduce the amount and weight of the material making up the member, and the central or intermediate portion is provided with a forwardly extending load-transfer portion 26. As best seen in FIGURE 4, the load-transfer portion 26 is offset from the center plane of the member, and the intermediate portion 22 is formed with a load-receiving portion or socket 28 in which is received the load-transfer portion of the other member to interlock the members together.

Depending downwardly and extending rearwardly from the central portion 22 is a leg or supporting portion 30 which is formed intermediate its ends with an annular shoulder or the like 32, to securely embed the leg 30 in the concrete. The leg 30 terminates in a foot portion 34 which is formed with a downwardly depending boss 36. The boss 36 is received in an aperture formed in a transversely extending rail 38, and the rail 38 serves to interconnect the legs 30 of the members positioned in the slab or section 18. Similarly, a rail 40 interconnects the feet of the members received in the section or slab 20. In both sections, the rails 38 and 40 are positioned on the subgrade 14 of the roadway.

Extending upwardly and rearwardly in the embodiment shown in FIGURE 2, from the intermediate or central portion 22, is a compression portion 42 which terminates at its outer end in an annular shoulder or leg 44 which serves to securely embed the portion 42 in the concrete. All of the portions 22, 30 and 42 are formed with integral ribs, indicated respectively by the reference numerals 46, 48, and 50, which serve to strengthen the respective portions. In the form shown in FIGURE 2, the plurality of pairs of members forming the road joint support arrangement are interconnected by a transversely extending plate 52.

Plate 52 is provided with a plurality of spaced apart apertures through which the load-transfer portions 26 of the complementary members pass where the plate 52 is supported by the plurality of pairs of members. The plate 52 is formed at its bottom edge with a turned under reinforcing rib 54, and plate 52 terminates a spaced distance below the surface of the adjacent sections of the concrete roadway, and when initially installed a U-shaped cap member 56 is carried by the plate 52.

In installation, the pairs of members are secured together at their road transfer portions by means of a pair of tapered pins 60 (see FIGURE 4) which are driven into complementary formed and positioned grooves 62 and 64, formed in the load-transfer portion 26 and the load-transfer-receiving portion 28 whereby as the tapered pins 60 are driven into the aperture formed by the grooves 62 and 64, the pairs of members will be rigidly inter-

locked or fixed together so as to prevent any vertical movement from taking place between the members. The interlocking of the two members is accomplished by the load-transfer and load-transfer-receiving portions 26 and 28, respectively, as is best seen in FIGURE 6. In that figure, the load-transfer-receiving portion 28 is shown as being in the form of a socket made up of an upper wall 66, a rear wall 68 and a bottom wall 70 in which the groove 64 is formed. The load-transfer portion 26 is complementary in shape of the socket 28 and is thus, received within the confines of the walls 66, 68 and 70 so as to prevent any vertical movement of the portion 26 within the socket 28.

Thereafter, the compressive members 42 are coated with a lubricant, as is the cap member 56 and then the concrete is poured between side forms 10 and 12. When the concrete becomes sufficiently hardened, the cap 56 is removed to form the joint of piece 21 which is finished by suitable tools, and after complete hardening of the concrete, is filled with any suitable type of deformable or compressible material.

As is well understood in the art, the plate 52 creates a plane of weakness between the adjacent slabs or sections of the roadway to control the location of the crack or fissure which will take place in the roadway after it is hardened due to the tensile and compressive forces set up by the contraction and expansion of the concrete. When such contraction takes place, if the force caused by the contraction is of sufficient magnitude, the tapered pins 69 are sheared to permit longitudinal or horizontal movement between the members forming each pair of the road joint support arrangement. This movement, however, will be of such small amount that the load-transfer and transfer-receiving portions 26 and 28 are still interlocked to prevent vertical displacement from taking place between the sections 18 and 20.

Referring now to FIGURES 3 and 4 wherein another form of the complementary members forming the road joint support are shown, the members comprise a central portion 122 having an aperture 124 formed thereon to reduce the amount and weight of the material used in forming the member, and to permit the concrete in sections 118 and 120 to pass through the aperture so securely grip the members. Extending forwardly from the center or intermediate portion 122 is the load-transfer portion 126 which is positioned adjacent to the load-transfer-receiving portion or socket 128. Depending downwardly and rearwardly from the central portion 122 is a leg portion 130 having an annular shoulder 132 and the leg portion terminates in foot portion 134, having a boss 136 depending from its underside.

Each of the members received in the section 118 are positioned in suitable apertures formed in transversely extending rail 138 which is positioned on the subgrade 14 of the roadway, and the members positioned in section 120, likewise, have their feet portion interconnected by a transverse rail 120.

Extending rearwardly from the central portion 122 is a compression portion 142 which terminates at its outer end in an annular shoulder 144. The portions 122, 130 and 142 are provided with strengthening ribs 146, 148 and 150.

The form shown in FIGURE 3 includes a portion 151 extending upwardly and rearwardly from the central portion 122 which also acts as a compression member. Similarly, to the manner described in connection with FIGURES 2 and 4, a plate 152 interconnects the pairs of members and extends transversely across the roadway

and is formed at its bottom with an inturned strengthening rib 144. Also carried between the members and adjacent the plate 152 is a fibrous expansion member 153 which rests on the subgrade surface 114 and extends upwardly between the pairs of members and terminates a spaced distance below the upper surface of the roadway. A removable shield or cap member 156 is mounted atop the expansion material 153 and the joint 62 may be finished in the manner described in connection with FIGURES 2 and 4.

Also as best seen in FIGURE 5, expansion material 157 is received in the load-transfer-receiving sockets 128 between the rear wall of the socket and the forward surface of the load-transfer portion 126. The portions 126 are rigidly connected to the sockets 128 by virtue of tapered pins 160 driven into the aperture formed by the aligned grooves 162 and 164 formed in the transfer members 126 and the socket members 128, respectively.

Referring to FIGURE 7, the joint support members of the embodiment shown in FIGURES 3 and 5, are securely interlocked together in the same fashion as the interlock described in connection with the embodiment shown in FIGURES 2 and 4. The socket forming the load-transfer-receiving portion 128 comprises an upper wall 166, a rear wall 168 and a bottom wall 170 in which the groove 164 is formed whereby the walls 166, 168 and 170 cooperate to prevent any vertical displacement of the load-transfer portion 126 within the socket 128.

The form of the invention shown in FIGURES 3 and 5 functions in the same manner as that described in connection with FIGURES 2 and 4 and the installation is identical to that described in connection with the first form of the invention.

What I claim is:

A road joint support for supporting adjacent sections of a roadway and for transferring a dynamic load on said roadway from one of said sections to the other, comprising a pair of complementary members joined together, one each of said members being positioned in one each of said sections and each member having a load-transfer portion extending across said joint and into engagement with the other member, means for wedging said members together in surface to surface contact at said load-transfer portions, each of said members including a support portion adapted to be positioned on the subgrade surface of said roadway, and a compression portion extending rearwardly, and a load-transfer-receiving portion formed adjacent said load-transfer portion, said means for wedging said members together comprising a pair of tapered drive pins driven into grooves formed in the load transfer and load receiving portions so as to urge the upper surface of the load transfer portion into engagement with the upper surface of the load receiving portion, and said members being joined together by said load-transfer and said load-transfer-receiving portions in surface to surface contact to prevent relative vertical movement therebetween for supporting said road joint.
